TAIL LAMP FOR AUTOMOBILE VEHICLES

Michel Tixier, Billancourt, France, assignor to Regie
 Nationale des Usines Renault, Billancourt, France

Filed Oct. 31, 1969, Ser. No. 19,875

Term of patent 14 years

Int. Cl. D12—99

U.S. Cl. D48—32

Fig. 1

Fig. 2

FIG. 3

FIG. 4

FIG. 5

FIG. 6

FIG. 1 is a front perspective view of a tail lamp for automobile vehicles showing my design;

FIG. 2 is a front perspective view thereof taken from another angle;

FIG. 3 is a top plan view thereof on a slightly enlarged scale;

FIG. 4 is a fragmentary sectional view taken on line 4-4 of FIG. 6 on a greatly enlarged scale;

FIG. 5 is a bottom plan view thereof on a slightly enlarged scale;

FIG. 6 is an end elevational view thereof on an enlarged scale.

I claim:

The ornamental design for a tail lamp for automobile vehicles, as shown and described.
